(57) **CLAIM**

The ornamental design for a grenade-shaped container, as shown and described.

DESCRIPTION

FIG. 1 is a perspective view of a grenade-shaped container showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a bottom perspective view thereof;

FIG. 9 is an exploded perspective view thereof;

FIG. 10 is an exploded rear elevational view thereof;

FIG. 11 is front view thereof, showing the plane upon which a cross-sectional view is taken and shown in FIG. 12;

FIG. 12 is a perspective cross-sectional view taken along line 12-12 of FIG. 11;

FIG. 13 is a perspective view showing a bottom piece of the grenade-shaped container, shown broken away for ease of illustration;

FIG. 14 is a rear perspective view thereof;

FIG. 15 is a bottom perspective view showing a top piece of the grenade-shaped container, shown broken away for ease of illustration; and,

FIG. 16 is a rear bottom perspective view thereof.
